[57] CLAIM

The ornamental design for snack tray, as shown.

DESCRIPTION

FIG. 1 is a pictorial view according to the first embodiment of the design;

FIG. 2 is a cross-sectional view generally taken along the longitudinal axis of the design shown in FIG. 1; FIG. 3 is a cross-sectional view like FIG. 2 except that the dashed lines illustrate the position of a person's hand while using the snack tray having this design;

FIG. 4 is a plan view of the snack tray whose design is shown in FIG. 1;

FIG. 5 is a bottom plan view of the snack tray whose design is shown in FIG. 1;

FIG. 6 is an elevation view of the side of the snack tray according to the design of the embodiment of FIG. 1; FIG. 7 is an elevation view of the end of the snack tray according to the design of the embodiment of FIG. 1; FIG. 8 is an elevation view of the side of the snack tray, other than the one shown in FIG. 6, according to the design of FIG. 1;

FIG. 9 is an elevation view of the end of the snack tray, other than the one shown in FIG. 7, according to the design of FIG. 1;

FIG. 10 is a pictorial view according to the second embodiment of the design;

FIG. 11 is a cross-sectional view generally taken along the longitudinal axis of the design shown in FIG. 10; FIG. 12 is a cross-sectional view like FIG. 11 except that the dashed lines illustrate the position of a person's hand while using the snack tray having this design;

FIG. 13 is a plan view of the snack tray whose design is shown in FIG. 10;

FIG. 14 is a bottom plan view of the snack tray whose design is shown in FIG. 10;

FIG. 15 is an elevation view of the side of the snack tray according to the design of the embodiment of FIG. 10; FIG. 16 is an elevation view of the end of the snack tray according to the design of the embodiment of FIG. 10; FIG. 17 is an elevation view of the side of the snack tray, other than the one shown in FIG. 15, according to the design of FIG. 10;

(List continued on next page.)

FIG. 18 is an elevation view of the end of the snack tray, other than the one shown in FIG. 16, according to the design of FIG. 10;

FIG. 19 is a pictorial view according to the third embodiment of the design;

FIG. 20 is a cross-sectional view generally taken along the longitudinal axis of the design shown in FIG. 19;

FIG. 21 is a cross-sectional view like FIG. 20 except that the dashed lines illustrate the position of a person's hand while using the snack tray having this design;

FIG. 22 is a plan view of the snack tray whose design is shown in FIG. 19;

FIG. 23 is a bottom plan view of the snack tray whose design is shown in FIG. 19;

FIG. 24 is an elevation view of the side of the snack tray according to the design of the embodiment of FIG. 19;

FIG. 25 is an elevation view of the end of the snack tray according to the design of the embodiment of FIG. 19;

FIG. 26 is an elevation view of the side of the snack tray, other than the one shown in FIG. 24, according to the design of FIG. 19;

FIG. 27 is an elevation view of the end of the snack tray, other than the one shown in FIG. 25, according to the design of FIG. 19;

FIG. 28 is a pictorial view according to the fourth embodiment of the design;

FIG. 29 is a cross-sectional view generally taken along the longitudinal axis of the design shown in FIG. 28;

FIG. 30 is a cross-sectional view like FIG. 29 except that the dashed lines illustrate the position of a person's hand while using the snack tray having this design;

FIG. 31 is a plan view of the snack tray whose design is shown in FIG. 28;

FIG. 32 is a bottom plan view of the snack tray whose design is shown in FIG. 28;

FIG. 33 is an elevation view of the side of the snack tray according to the design of the embodiment of FIG. 28;

FIG. 34 is an elevation view of the end of the snack tray according to the design of the embodiment of FIG. 28;

FIG. 35 is an elevation view of the side of the snack tray, other than the one shown in FIG. 33, according to the design of FIG. 28; and,

FIG. 36 is an elevation view of the end of the snack tray, other than the one shown in FIG. 34, according to the design of FIG. 28.

The broken line showing of a hand in FIGS. 3, 12, 21, and 30 is for illustrative purposes only and forms no part of the claimed design.
